UNITED STATES PATENT OFFICE.

ARTHUR C. LILLIE, OF LOS ANGELES, CALIFORNIA.

DESIGN FOR A WIND-SHIELD FOR AUTOMOBILES.

53,923.

Specification for Design.

Patented Oct. 7, 1919.

Application filed March 10, 1919. Serial No. 281,862. Term of patent 14 years.

To all whom it may concern:

Be it known that I, ARTHUR C. LILLIE, citizen of the United States, residing at Los Angeles, in the county of Los Angeles, State of California, have invented a new, original, and ornamental Design for a Wind-Shield for Automobiles, of which the following is a specification, reference being had to the accompanying drawing, forming a part thereof.

The figure is a perspective view of a wind-shield for automobiles, showing my new design.

I claim:

The ornamental design for a wind-shield for automobiles, as shown.

ARTHUR C. LILLIE.
